UNITED STATES PATENT OFFICE.

BENJAMIN H. QUICK, OF DES MOINES, IOWA, ASSIGNOR TO THE HART & COOLEY COMPANY, OF NEW BRITAIN, CONNECTICUT, A CORPORATION OF CONNECTICUT.

SETTING-FRAME FOR SIDE-WALL REGISTERS.

1,162,398.

Specification of Letters Patent. Patented Nov. 30, 1915.

Application filed April 24, 1915. Serial No. 23,737.

To all whom it may concern:

Be it known that I, BENJAMIN H. QUICK, a citizen of the United States, residing at Des Moines, Polk county, State of Iowa, have invented certain new and useful Improvements in Setting-Frames for Side-Wall Registers, of which the following is a full, clear, and exact description.

My invention relates to a new means for facilitating the installation of hot air registers, and consists particularly in what I may term a setting frame or gage.

The object of the invention is to provide a relatively cheap and simple device which may be installed in a building during the process of erection to facilitate the application of a register of the side wall type after the floors and trim are finished.

The advantage of the construction will be readily apparent to any one familiar with the art from a reading of the following specification and an examination of the accompanying drawing which shows the invention in its preferred form only.

In the drawings, Figure 1 is a front elevation partly broken away of the lower part of a register with a portion of the adjacent side wall and part of the setting gage shown in place. Fig. 2 is a side section on the plane of the line 2-2, Fig. 1. Fig. 3 is a section on the plane of the line 3-3, Fig. 2, and relatively reduced in size. Fig. 4 is a perspective view of the setting gage in its preferred form.

In the drawings 1-1 represent partition studs.

2-2 represent lath secured to said studing at each side of the register passage.

3-3 represent the plastering at each side of said passage.

4-4 represent the ends of the base board at each side of said register passage.

5 represents the flue outlet box, or so-called stack head, to which the register proper is secured in the usual manner.

6 represents the front of a side-wall register which is in the main of conventional type, and is provided with the side walls 7-7 and a perforated grid 8.

The setting gage illustrated in detail in Fig. 4 comprises the main body or bridge portion 9 which is preferably provided with right angle bends to form side members 10-10. The bridge is preferably provided with one or more strengthening corrugations

11-11 or other suitable reinforcing means to stiffen the front and sides. The side members 10-10 may be so formed and spaced as to receive and hold the outlet end of the stack head 5, where it comes through the floor 12. The sides 10-10 at their rear ends are flanged outwardly to form seats 14-14 designed to bear against the studs 1-1 to which the setting gage may be secured by any suitable fastening means such as nails 15-15.

16-16 are shoulders preferably formed by bending the ends of the seats 14-14 outwardly as shown. These shoulders 16-16 are spaced at a predetermined distance from each other so that they will constitute stops for the lath, plaster and base board at each side of the flue passage. It has been common practice to provide separate stop shoulders for this purpose, but the use and application of separate stop shoulders requires an unnecessary amount of labor and skill in locating the same in the proper position, as accurate measurements have to be made, marks established, and great care exercised in applying the same at the designated positions. By my invention, the correct position of the stop shoulders is guaranteed and to apply the same requires no special skill or careful preliminary measurements. Again, by my improvement, the bridging member, by which the stops are held in predetermined positions, performs the additional function of a holding means for the stack head 5. The lower rear edges of the sides 7-7 may be indented or cut away slightly so as to afford clearance for the ends 16-16 of the setting frame, as best seen in Fig. 3. As these positions are near to the meeting line of the wall and floor, it is obvious that the base board ends 4-4 will cover the same.

What I claim is:

1. A setting frame for side-wall registers and the like comprising, a main bridging member, stops at the ends thereof held in predetermined spaced relation thereby and forming stops for the base-board.

2. A setting frame for side-wall registers and the like comprising, a main bridging member, stops at the ends thereof and held in a predetermined spaced relation thereby and forming stops for the base-board, said bridging member being offset forwardly relatively to said stops.

3. A setting frame for side-wall registers

comprising, a main bridging member the middle portion thereof being offset, seats at the ends of said bridging member and constituting part thereof, and stops at the ends of said bridging member extending outwardly relatively to said seats to form stops for the ends of the base-board at each side

of the register opening, said stops being held in predetermined spaced relation by said bridging member.

BENJAMIN H. QUICK.
